ELECTRIC SIGNALING SYSTEM

Harold Mountjoy Muschamp d'Assis-Fonseca and
 Hugh Jennings Ward, London W. C. 2, Eng-
 land, assignors, by mesne assignments, to In-
 ternational Standard Electric Corporation,
 New York, N. Y., a corporation of Delaware

Application February 27, 1943, Serial No. 477,388
 In Great Britain April 14, 1942

10 Claims. (Cl. 177—353)

This invention relates to electric signaling systems, and will be described in its application to electric power supply networks, where equipment, such as circuit breakers, located remotely from a control station, has to be controlled from that central station. By way of example, mention may be made of our prior British patent specifications Nos. 489,000 and 514,991 as disclosing electric remote control and/or supervisory systems which could make use of the present invention.

An electric signaling system is known in which information is conveyed by a train of impulses which vary individually in polarity and length. The present application discloses an equipment for the reception of such a train of impulses.

The nature or delimitation of the invention is particularly ascertained in the claiming clauses of the statement of the invention claimed which ends this specification; whilst the further description of the invention, and the particular description and ascertainment of the manner in which the invention is to be performed, will be provided in what now follows, showing, with the aid of the accompanying drawing, how best the applicants have been able, up to the present, to carry the invention into effect.

The invention will be described with reference to the accompanying drawing, in which:

Fig. 1 shows the basic circuit of a receiver for trains of impulses which may vary individually both in polarity and in length; and

Fig. 2 shows the operation of this receiver by means of a time-chart.

Referring to Fig. 2, showing in a diagrammatic manner the sequence of operations during receipt of a train of impulses, this train is supposed, for the sake of example, to consist of a long seize pulse, a short prepare pulse, six code pulses, and a marking out pulse, the fourth code pulse being lengthened. The polarity of the individual pulses may be ignored for the moment, since the operations are those dependent upon the common relay IR. The impulses are assumed to have a 50:50 ratio, with the long code pulses three times the length of the short.

At the arrival of an impulse train, relay IP or IN, responding to a signal of the proper polarity received over the line L, is energized. Either relay IP or IN operates relay IR which, in turn, energizes the slow-releasing relay G which remains energized until the final de-energization of relay IR at the end of an impulse train.

During the seizing impulse, relay C remains de-energized. Its energizing circuit contains 55

contacts SRON which are closed in the home position and opened in any other position of switch SR. In series with contacts SRON are relay contacts G2 and contacts IR1' which are opened when IR is energized and closed when IR is de-energized.

In the first case, IR1' is disconnected from its front contact through the pressure exerted by the back contact of IR1 against its associated front contact.

At the end of the seize impulse, relay IR is released and thereby slow-releasing relay C is energized via contacts SRON which are still closed. Relay C remains operated over its own contacts 15 C3 via: minus battery, relay C, contacts C3, G2, IR1', plus battery: its release time is such that it releases during the marking-out pulse when IR1' is held open for a time exceeding the length of the individual code pulses.

20 At the beginning of the second and of each subsequent impulse, relay IR is energized and the magnet SRM becomes energized via contacts C1 and IR1. Switch SR which stands normally on its first or home contact is made to take one 25 step upon de-energization so that during each subsequent impulse, its wipers SR1, SR2, SR3, and SR4, stand in different positions on their associated contact banks. When relay G releases after the marking-out pulse, then magnet SRM 30 is under control of wiper SR1 through stepping contacts ST and the switch SR returns to normal.

With the operation of relay G, relay P1 is energized via contacts C2 and G1. The coil of relay P1, after the first release of relay IR, remains 35 energized via: minus battery, relay P1, IR2, G2, plus battery. Thereafter, it is disconnected by each subsequent energization of IR whether short or long, by the opening of back contact IR2. Pendulum contact P11 in its operation lags behind the energization and de-energization of the coil and swings back and forth at its natural frequency between the two fixed contacts, when the coil is de-energized. This occurs during the long duration pulse following the first three code pulses 40 of normal duration. During this long code pulse, pendulum contact P1 continues to swing and thereby transmits a positive signal to bank contacts LPM via: SR4, P11 right, PM1, IR2 front, G1, plus battery.

45 Relay PM itself is energized whenever P1 is de-energized, i. e., when pendulum contact P11 is in its left-hand position. It will normally not be energized when P11 is in its right-hand position, except via contacts PM1, IR2 front, i. e., during

the long duration impulse and during the marking-out impulse.

Each time relay P1 is energized by the release of relay IR the pendulum contact P11 is connected to the wiper SR4 of the switch SR, but no potential is delivered to this wiper because relay PM releases when relay P1 is energized thus opening contacts P11 and the release of relay IR opens contacts IR2 front. However when relay IR is held up by an incoming pulse longer than the period of the pendulum relay P1, the pendulum contacts P11 of this relay continue to close intermittently because of the natural swing of the pendulum without the energization of relay P1. Because relay IR is operated, relay PM remains locked over contact PM1, front contact IR2, and contact G1 to plus battery, and this same circuit applies a positive potential to wiper SR4 each time the pendulum contact P11 touches the right fixed contact. These intermittent positive potentials will continue to be applied for the remainder of the duration of the long incoming pulse while the wipers of switch SR remain in the same position. When the IR relay releases at the end of the long pulse the pendulum contact P11 will be moving towards the coil of relay P1 to be held there again as the P1 relay is energized.

It will be seen that when a pulse train is received the SR switch will start to step and will make one step for each pulse. Positive potentials are then delivered to each of the contacts of the PPM bank or the NPM bank through wipers SR2 and SR3, depending on whether the pulses are positive or negative. As long as short pulses continue to come in no potentials are applied to the contacts of the LPM bank, but when a long pulse is received then pulses of positive potential are delivered to the particular contact of this bank upon which wiper SR4 is resting at the time by the free operation of pendulum contact P11, the number of pulses being determined by the length of the incoming long pulse.

When more than one train of impulses are received in succession, relay G is not released until the end of all of these, and the above cycle is repeated for each subsequent train.

What is claimed is:

1. A receiver for a series of successive electrical code pulses, comprising relay circuit means controlled by the pulses and controlling code-operated circuit means, including a pendulum relay having an armature adapted, upon energization derived from intervals between said code pulses, to execute a natural oscillation for substantially the normal duration of a code pulse, and to execute additional natural oscillations when de-energized for the duration of an extended pulse of more than normal length, and circuit means controlled by at least some of said additional oscillations to produce a signal indicative of said extended code pulse.

2. A receiver for a series of successive electrical code pulses, comprising relay circuit means controlled by the pulses and controlling a number of code-operated circuits corresponding to said series of code pulses, distributor means operated by said relay circuit means to connect successively said relay circuit means with said code-operated circuits, a pendulum relay controlled by said circuit means and having an armature adapted, during intervals between said code pulses, to execute a natural oscillation for substantially the normal duration of a code pulse, and to execute addi-

tional natural oscillations when a code pulse is of longer than normal duration, and armature contacts operated by said additional oscillations to energize at least one of said code-operated circuits.

3. A receiver according to claim 1, wherein the armature of said pendulum relay is adapted, following an energization, to execute one oscillation between opposite stationary contacts, and to continue oscillating for a time after said energization has ceased.

4. A receiver according to claim 1, wherein said code-operated circuit means consists of a pulse-operated multi-bank sequence switch, each bank having a series of stationary contacts and a wiper arranged to be moved along said contacts, one of said wipers being connected to receive pulses derived from positive code pulses, a second wiper being connected to receive pulses derived from negative code pulses, and a third wiper being connected to receive pulses controlled by additional oscillations of the pendulum relay.

5. A receiver for a series of successive electrical code pulses of different polarity and length, comprising a pair of receiving relays across a signal circuit and connected to be operated by positive and negative code pulses respectively, a repeater relay having two energizing circuits each controlled by one of the receiving relays, a first series 30 of distributor circuits derived from said pulses and controlled by one of said receiving relays to indicate the positive characteristic of a code pulse, a second series of distributor circuits derived from said code pulses and controlled by the other of said receiving relays to indicate the negative characteristic of a code pulse, a third series 35 of distributor circuits derived from said code pulses, a pendulum relay having an energizing circuit to be energized by said repeater relay during intervals of said code pulses, and having an armature adapted, upon energization, to execute a natural oscillation for substantially the normal duration of a code pulse, and to execute additional natural oscillations after said energizing circuit has been de-energized for an extended 40 code pulse of more than normal duration, pendulum relay contacts controlled by said additional oscillations and controlling said third series of distributor circuits to indicate the length of a code pulse, said energizing circuit being energized when a repeater relay is operated by the seize pulse, and a further relay operated by said pendulum relay to prevent said energizing circuit from being energized when said repeater relay is deenergized.

6. A receiver according to claim 5, wherein said distributor circuits form part of a pulse-operated multi-bank stepping switch, operated by contacts of the repeater relay interrupting the pulse current for each pulse of the code, said stepping switch comprising first and second banks of contacts, successive contacts of which, in each of the successive positions of the switch, are connected to receiving relays operated by negative and positive code pulses, respectively, to indicate the polarity of said code pulses, said stepping switch further comprising a third bank of contacts, successive contacts of which, in each of the successive positions of the switch, are connected to pendulum relay contacts to indicate the length of said code pulse.

7. A receiver according to claim 5, wherein said distributor circuits form part of a pulse-operated multi-bank stepping switch operated by contacts of the repeater relay interrupting the pulse cur-

rent for each pulse of the code, said stepping switch comprising a bank having a home position circuit operating slow-releasing relay means under the control of seize and prepare pulses preceding the code pulses, and operating a further relay to prepare a circuit connection between contacts of the pendulum relay and a further contact bank of said stepping switch as soon as the repeater relay is operated by pulses constituting the code.

8. A receiver according to claim 1, wherein said relay circuit means consists of two relays connected across the transmission line, each connected in series with a rectifier so as to respond to pulses of opposite polarity.

9. A receiver according to claim 1, wherein said relay circuit means consists of two relays connected across the transmission line, each connected in series with a rectifier so as to respond to pulses of opposite polarity, and wherein said distributor means consists of a pulse-operated multi-bank sequence switch, each bank having a series of stationary contacts and a wiper arrange-

ment to be moved along said contacts, two of said wipers being controlled each by one of said two relays and connected to receive pulses derived from negative and positive code pulses, respectively, a third wiper being connected to receive signals controlled by additional oscillations of said pendulum relay.

10. A receiver according to claim 1, wherein said relay circuit means consists of a repeater relay having contacts to control a first slow-releasing relay, said first slow-releasing relay being connected to operate contacts controlling a second slow-releasing relay at the end of the first pulse received, said second slow-releasing relay connected to control the current supply for the successive operations of said code operated circuit means and for the circuit means controlled by additional oscillations of said pendulum relay.
